(57) **CLAIM**

The ornamental design for a fireproof document bag, as shown and described.

DESCRIPTION

FIG. 1 is a perspective view of a fireproof document bag showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of the fireproof document bag in which the new design is embodied that form no part of the claimed design.
